UNITED STATES PATENT OFFICE.

GEORGE A. WISE, OF PITTSBURGH, PENNSYLVANIA, ASSIGNOR TO SUTTON-ABRAMSEN ENGINEERING COMPANY, OF PITTSBURGH, PENNSYLVANIA, A CORPORATION OF PENNSYLVANIA.

STRAIGHTENING ROLL.

Application filed February 15, 1923. Serial No. 619,113.

This invention relates to a special roll for use in a machine for the straightening of metallic bars and tubes of circular cross section, for example bars and tubes of steel and 5 aluminum.

The general type of machine for use with which the roll of the present invention is particularly designed is that of the machine shown in the patent to Petter B. Abramsen 10 No. 1,097,281, dated May 19, 1914.

In the accompanying drawings Figure 1 is a front elevation of a straightening machine of the general type mentioned above; Fig. 2 is a side elevation of a set of straightening rolls as mounted in such machine; Fig. 3 is a plan view of such set of straightening rolls; Fig. 4 is a horizontal section through such set; Fig. 5 is a side elevation, on an enlarged scale, of a straightening roll 20 made according to the present invention, illustrating the derivation of the curves forming the concave face of the roll, and showing the contact of two bars of different diameter with such face; Fig. 6 is an end elevation 25 of the roll, further illustrating the derivation of the curves forming the face thereof, and showing the contact of the two bars with the face of the roll at different points therealong; and Fig. 7 is a mathematical 30 diagram illustrating graphically the derivation of the curves forming the face of the roll.

In such machines the bars and tubes are carried between positively driven rolls, having 35 concave faces, and smaller idler rolls the faces of which are also concave. Both the driven rolls and the idler rolls are set in the frame or housing of the machine at an angle to the horizontal determined with 40 reference to the diameter of the bars undergoing a straightening operation.

In conducting a straightening operation it is highly important that the bar passing 45 through the machine should have a line contact rather than a point contact with the face of each of the main or driven rolls, such line contact extending a considerable proportion of the length of the face. Failure to provide such line contact results in "scrolling" 50 the surface of the bar, that is in imposing upon the surface of the metal a spiral twist. Previously, therefore, it has been a practical necessity to change the angle at which the rolls are mounted in the housing in order 55 to adjust the machine for the straightening

of bars of different diameter; this being a necessarily slow and delicate task requiring the services of a man skilled in such particular operation.

It is also a fact that when a line contact 60 is provided there is a tendency, particularly before the rolls have been worn in, for the extremities of the bars to be kinked owing to the fact that they do not immediately center themselves in passing from roll to 65 roll. These kinks require the scrapping of an appreciable quantity of metal cut from the ends of the bars.

One object of the present invention is to provide a roll having a face so formed that 70 bars of various diameters, within the limits for which each particular roll is formed, will have a true line contact of adequate extent therewith.

Another object of the invention is to provide 75 a roll so formed that bars may center themselves on the faces of successive rolls and pass smoothly through the machine without such buckling or snapping as would tend to produce kinks or bends in the ex- 80 tremities of the bars.

The manner of attaining the first object, generally stated, is to form the face of the roll on a plurality of arcs intersecting at a point or points part-way of the length of 85 the roll, so that bars of different diameter may find their line contact on different portions of the roll.

The manner of attaining the second object, generally stated, is to so form the roll 90 that the diameter at one end of the face thereof is slightly greater than the diameter at the other end of the face. This also obviates the disadvantage of a slight ridge or peripheral rib, which would otherwise be 95 present at the point of intersection of the arcs if the arcs were those of circles of equal radii.

Although the roll as shown and described 100 presents a combination of both such advantages, it will be seen subsequently herein that a roll may be made which presents either of such advantages alone.

As shown in Figs. 1 to 4 inclusive of the drawings, the arrangement of a machine may 105 be such that two positively driven rolls 1, such as those of the present invention, are mounted in series in the frame of the machine at an angle to the horizontal. Co-operating with these positively driven rolls 110

1 are smaller idler rolls 2, which are mounted at an equal and opposite angle to the horizontal. In the set of rolls shown three of such idler rolls 2 are employed; one of such rolls being mounted opposite each of the main rolls 1, and a third idler being mounted intermediately thereof. As the bar 3 passes through the machine it is gripped by the rolls in the manner shown in Figs. 3

10 and 4 of the drawings.

As shown diagrammatically in Figs. 5 and 6 of the drawings, bars of different diameter find their line contact with different portions of the face 4 of the roll. In Fig. 5 a bar 5 of the maximum diameter which the particular roll shown is designed to accommodate is shown in contact with the face of the roll, and a bar 6 of the minimum diameter which the roll shown is designed to accommodate is also shown in contact with the face thereof. Approximately only such portions of each bar as actually lie in contact with the face 4 of the roll are shown in this figure of the drawings. In Fig. 6 the same two bars 5 and 6 are shown in contact with the face of the roll. In this figure, however, the bars are shown in duplicate; the diagrammatic representation of the bar 5 designated 5^a indicating the contact of the bar with the circumference *a* (or diameter "D_a") of the roll, and the representation designated 5^b indicating the contact of the bar with the circumference *b* (or minimum diameter) of the roll. Similarly the diagrammatic representation 6^c indicates the contact of the smaller bar 6 with the circumference *b* (or minimum diameter) of the roll, and the representation 6^e indicates the contact of such bar with the circumference *c* (or maximum diameter "D max") of the roll.

These figures represent the positions of bars of four inch diameter and of a two inch diameter in their contact with the face of a roll designed specially to accommodate bars of a diameter within these limits. If the diameter of a bar passing through the rolls be of a diameter between four inches and two inches, its line of contact will obviously be intermediate that of the bars of extreme diameter shown, and will partially overlap the lines of contact of both thereof.

For the formation of a roll of the type shown a general formula has been deduced. That is, within limits, this formula may be applied for the formation of a roll accommodated to bars having certain extremes of diameter, and to bars of diameters intermediate these extremes. The general characteristics of such roll are that its face be formed on two intersecting curves which are the arcs of circles; because of the desirability for a lesser diameter at the entering than at the leaving end of the roll, that these arcs be those of circles of different diam-

eter, and that the roll be mounted at an angle "Q" to the horizontal.

With reference to Figs. 5 and 6 of the drawings, this formula is as follows:

$$C = \frac{L}{2} \tan Q. \quad 79$$

$$R_{\max} = \frac{D_{\max}}{2}. \quad 79$$

$$R_{\min} = \sqrt{\left(R_{\max} + \frac{X}{2}\right)^2 - C^2} - \frac{X}{2}. \quad 79$$

$$D_{\min} = 2R_{\min}. \quad 79$$

$$R_x = \sqrt{\left(R_{\min} + \frac{Y}{2}\right)^2 + C^2} - \frac{Y}{2}. \quad 80$$

$$D_x = 2R_x. \quad 80$$

$$S = R_{\max} - R_{\min}. \quad 80$$

$$\text{Radius } A = S^2 + \frac{(L)^2}{2} \quad 85$$

$$T = R_x - R_{\min}. \quad 85$$

$$\text{Radius } B = T^2 + \frac{(L)^2}{2} \quad 90$$

$$2T \quad 90$$

In the foregoing formula "C" is a constant comprising the product of one half the total line contact of the face of the roll and the tangent of the angle at which the roll is set to the horizontal.

"R min" is the least radius of the face of the roll, occurring at the median cross sectional line thereof. It is the square root of the square of the sum of the greatest radius of the face of the roll "R max" and the radius of the bar of least diameter which the roll may accommodate $\frac{x}{2}$, minus the square of "C", or the product of one half the total line contact and the tangent of the angle "Q" which the axis of the roll forms with the horizontal; less the radius $\frac{x}{2}$ of the bar of least diameter.

"R_x" is the radius of the face of the roll at the entering end thereof, being greater than "R min" but less than "R max". It is the square root of the square of the sum of the least radius "R min" of the effective face of the roll and the radius $\frac{Y}{2}$ of the bar of greatest diameter which the roll may accommodate, plus the square of "C" or the product of one half the total line contact and the tangent of the angle "Q" which the axis of the roll forms with the horizontal; less the radius $\frac{Y}{2}$ of the bar of greatest diameter.

"S" is a quantity representing the difference of the greatest radius of the roll face, 130

that at the leaving end thereof, and the least radius of the roll.

"T" is a quantity representing the difference of the radius of the roll at the entering end thereof and the least radius of the roll.

Radius A, derived as indicated in the formula, is the radius on which the rearward half of the roll is turned.

Radius B, derived as indicated in the formula, is the radius on which the forward or entering half of the roll is turned.

The following concrete example is derived by substituting in the formula the definite figure for a particular roll. Such roll, which is the one specifically illustrated herein, is a roll designed to provide line contacts for bars of from two inches to four inches. In order to secure the most favorable condition for such range, "D max" is eleven and one-fourth inches ($11\frac{1}{4}$ "), the total length of the double line contact is sixteen and one-half inches ($16\frac{1}{2}$ "), and the angle "Q" formed by the center line of the roll with the horizontal of the pass is twenty degrees (20°).

With these substitutions the formula for the roll shown would read as follows:

$$C = 8\frac{1}{4} \cdot \tan 20^\circ = 8\frac{1}{4} \cdot 0.36397 = 3.003".$$

$$C^2 = 9.018009.$$

$$R \text{ max} = \frac{11\frac{1}{4}}{2} = 5.625".$$

$$R \text{ min} = \sqrt{(5.625 \times 1)^2 - 9.018009} - 1 = 4.897.$$

$$D \text{ min} = 2 \cdot 4.897" = 9.794.$$

$$Rx = \sqrt{(4.897 \times 2)^2 + 9.018009} - 2 = 5.522".$$

$$Dx = 2 \cdot 5.522 = 11.044".$$

$$S = 5.625 - 4.897 = .728".$$

$$T = 5.522 - 4.879 = .625".$$

$$Radius A = \frac{(.728)^2 + 68.0625}{1.456} = 47.110".$$

$$Radius B = \frac{(.625)^2 + 68.0625}{1.260} = 54.722".$$

It will be seen that the formula given is such as to provide for any bar within the desired limits a line contact equal to one-half the entire face of the roll, as is shown in Fig. 5 of the drawings. That is, during rotation of the roll the bar has such a line contact at any instant with some line of points on the surface of the roll. This is obviously the maximum line contact which can be provided for uni-cross sectional bars of various diameters within the limits for which the roll is designed.

It should also be understood that the essence of the present invention resides in the provision of the plural line contact along the face of the roll and in the various diameters thereof, and not in the specific formula for the formation of any particular roll. A number of variations in the roll are, therefore, within the knowledge and power of a skilled mechanical engineer and mathematician without departing from the spirit of the invention. Thus the roll may be so formed as to provide a plural instead of a double line contact, or the face of the roll may be formed on curves other than the arcs of circles.

The scope of the invention is therefore to be restricted only by the limitations contained in the appended claim.

What I claim is:

A roll for use in a machine for straightening metallic rounds having its face formed as a surface of revolution generated by a plane curve revolving about a line in its own plane with its concavity facing outward from its line of revolution, said curve being composed of the arcs of two circles of different radius length tangent to the same line at their meeting point.

In witness whereof, I hereunto set my hand.

GEORGE A. WISE.
